UNITED STATES PATENT OFFICE.

JOHN THOMAS LUCAS, OF WASCO, OREGON.

GANG OR CULTIVATOR PLOW.

SPECIFICATION forming part of Letters Patent No. 634,358, dated October 3, 1899.

Application filed November 4, 1898. Serial No. 695,465. (No model.)

To all whom it may concern:

Be it known that I, JOHN THOMAS LUCAS, of Wasco, in the county of Sherman and State of Oregon, have invented a new and Improved 5 Gang or Cultivator Plow, of which the following is a full, clear, and exact description.

The principal object of my invention is to improve upon the construction of gang or cultivator plows for which Letters Patent were 10 granted to me June 27, 1893, No. 500,405.

A further object of the invention is to provide a rear or guide wheel which will have but slight frictional engagement with the land and to provide means for simultaneously raising 15 and lowering all of the shares and for leveling the plow when necessary.

A further object of the invention is to provide an adjustable clevis and a simple means for operating the same and to provide the 20 shares with detachable landsides, whereby the shares will be prevented from slipping upon hilly or upon uneven ground.

The invention consists in the novel construction and combination of these several parts, 25 as will be hereinafter fully set forth, and pointed out in the claims.

Reference is to be had to the accompanying drawings, forming a part of this specification, in which similar characters of reference indicate 30 corresponding parts in all the figures.

Figure 1 is a plan view of the improved plow. Fig. 2 is a side elevation of the same, and Fig. 3 is a detail perspective view of the shank for the rear shaft and the share belonging to the 35 shank.

The frame of the body of the implement consists, primarily, of two side beams A and B and two intermediate beams C and C'. The right-hand side beam B is of zigzag shape, being 40 bent to form a series of steps, (designated as b.) The intermediate beams C and C' extend beyond the front portion of the two outer or side beams, while at the rear end of the plow the two side beams are brought together 45 and the projecting forward ends of the intermediate beams C and C' are given a downward inclination, as shown in Fig. 2.

The side and intermediate beams are connected or braced together by cross-bars 10 and 50 11, while a cross-bar 12 extends through the inclined projecting portions of the intermediate beams, and another cross-bar 13 is pro-

vided for the said projecting portions of the intermediate beams at their forward extremities.

Two parallel axles D and D' are provided for the frame of the plow, the said axles being located near the front end of the plow and are journaled in suitable bearings carried by the side frames A and B. The forward axle 60 D is provided with a crank-arm 14 at its right-hand end, carrying a supporting-wheel 14^a, while the rear axle D' is provided with a crank-arm 15 at its left-hand end, which carries a supporting-wheel 15^a, the two supporting-wheels being practically in transverse alignment.

A hand-lever 16 is secured upon the straight portion of the forward axle D, near its crank-arm, and the said hand-lever is provided with a thumb-latch 17, adapted to engage with a suitable rack 18 on the frame, and a second hand-lever 19 is secured upon the straight portion of the rear axle D', near its crank-arm, the lever 19 being also provided with a thumb-latch 20, adapted to engage with a rack 21, also secured to the frame. By manipulating the lever at the left of the frame and attached to the rear axle the plowshares may be raised and lowered and made to travel 80 at any desired depth in the soil, while through the medium of the lever attached to the front axle the wheel that travels in the furrow may be raised and lowered independently of the landside-wheel, so as to level the plow.

At the front end of the plow-frame a clevis 22 is located, the said clevis being of angular construction. One member of the clevis is adapted to travel upon the front connecting-rod 13, while the other member is provided 90 with a series of apertures 23, adapted to receive a draft device, and the clevis is laterally shifted through the medium of a hand-lever 24, fulcrumed, preferably, upon the connecting-rod 12, as shown in Figs. 1 and 2, 95 the forward end of the lever having shifting engagement with the clevis. When the clevis is constructed in the manner set forth, it may be shifted to vary draft to and from the land while the plow is in motion, and the loop connection 24^a, which is provided between the clevis and the lever, serves to prevent the lever binding on uneven ground, and the loop connected with the clevis-lever 24 is con-

nnected with the clevis through the medium of a pin 24^a, as is particularly shown in Fig. 2. The clevis-lever 24 is provided with a suitable projection adapted to engage with the rack 25, and the rear ends of all of the levers are within convenient reach of the driver's seat 25^a, said seat being mounted upon the rear portion of the frame.

The plowshares 26 are somewhat rectangular in general contour, but their forward faces are concaved and their rear faces convexed, and one or more of the plows are provided with a landside 27, the landsides being attached to the rear face of the share by means of lugs 28, and where a landside connects with a share the outer face of the landside is more or less convexed. The end of a landside farthest removed from a share is connected with said share by a brace 30, and the said braces and likewise the landsides are detachably attached to the shares, as the shares are reversible, both their upper edges 26^a and lower edges 26^b being cutting edges.

All of the shares with the exception of the rear share are connected with the zigzag bar B through the medium of shanks 29, the upper ends of the shanks being provided with heads that are bolted or otherwise secured to the steps b of the said zigzag bar; but the shank 31 of the rear share, while it is attached in like manner to the rearmost step of the frame, is provided with an integral sleeve 32, which sleeve serves to journal a vertical shaft 33, and the said shaft at its lower end carries a fork 34, the fork being slightly inclined, so as to give an inclination to the rear guide-wheel 34^a, which guide-wheel is provided with a beveled edge and is adapted to engage with the land. A washer 35 is located on the shaft, journaling the guide-wheel 34^a at each side of the hub, said washers serving as caps, and they form dust-protectors and likewise prevent the earth working into the hub of the said guide-wheel. By constructing the rear shank 31 as shown in Fig. 3 it is made compact and strong, and but one piece is necessary where two pieces have heretofore been employed.

The shaft 33 is provided with a collar 36 near its lower end, which engages with the

bottom of the sleeve 32, and upon the upper end of the shaft 33 an arm 37 is secured, which usually extends forwardly and is prevented from moving toward the land by a pin 38, with which it engages, the pin being carried by the frame; but the arm is capable of moving to the right upon a suitable guide 39, provided for it. Thus it will be observed that the guide-wheel 34^a will take care of itself when the plow is turned and need not be operated by hand.

The landsides 27, attached to the shares, prevent the said shares from slipping upon hilly or upon uneven ground. The landsides are so shaped as to dispense with most of the friction common to other landsides, since the lower edges of the landsides are sharpened their full length, whereas the ordinary landsides are very wide at the bottom. The improved shares and landsides are especially adapted to plows supported upon three wheels, as there is little pressure between the land and the bottom of the shares and their landsides, thus reducing the draft to about one-half less than that of other plows turning the same width. The landsides can be readily detached when it is necessary to reverse the shares or to remove them for sharpening.

Having thus described my invention, I claim as new and desire to secure by Letters Patent—

1. In a gang-plow, the combination with a frame, of a plowshare having a shank attached to the share and fixed to the frame, a sleeve carried rigidly by the shank, a vertical shaft mounted in the sleeve, a rear guide-wheel supported by the vertical shaft at the lower portion thereof, an arm attached to the vertical shaft and extended forwardly, a guide over which the arm moves, and a pin carried by the frame and serving to limit the movement of the arm in one direction.

2. A plow, having a share, a landside connected with the share and having a cutting or sharpened lower edge, and means for bracing the landside against the share.

JOHN THOMAS LUCAS.
